UNITED STATES PATENT OFFICE.

HOWELL W. WRIGHT, OF GLASTENBURY, ASSIGNOR TO AUGUSTINE L. ELLIS, OF HARTFORD, AND ALBERT CHAPMAN, OF GLASTENBURY, CONNECTICUT.

DESIGN FOR COFFIN-HANDLE TIPS.

Specification forming part of Design No. 7,966, dated December 29, 1874; application filed December 12, 1874.
[Term of Patent 3½ years.]

To all whom it may concern:

Be it known that I, HOWELL W. WRIGHT, of Glastenbury, in the State of Connecticut, have invented or produced a Design for Coffin-Handle Tips, of which the following is a specification, and the accompanying drawing represents the said tip.

The base *a* of the handle-end is circular, and ornamented with bead-work. From this base the ornamental end is contracted, and then enlarges again, this portion being formed by leaves, as represented at *b*. Leaflets *c* are introduced between the scroll-ornaments *d*, that are at the ends of the leaves *b*, somewhat simi-

lar to a Corinthian capital. A circular base, *i*, next to these scrolls *d*, terminates with double leaflet ornaments *l* at the end of the tip.

I claim—

The ornamental design of the handle-tip, with leaves, scrolls, and leaflets, arranged as represented.

Signed by me this 7th day of October, A. D. 1874.

H. W. WRIGHT.
